(57) **CLAIM**

The ornamental design for a fine dry-bulk commodity container with insert, as shown and described.

DESCRIPTION

FIG. 1 is a front view of a fine dry-bulk commodity container with insert;

FIG. 2 is a back view of FIG. 1;

FIG. 3 is a right-side elevation view of FIG. 1;

FIG. 4 is a left side elevational view thereof, the opposite side being a mirror image thereof;

FIG. 5 is a perspective of the cargo pouch in a folded configuration; and

FIG. 6 is a left side elevational view of the cargo pouch in folded configuration, the opposite side being a mirror image thereof; and,

FIG. 7 is a perspective view of the fine dry-bulk commodity container with insert.
